(57) **CLAIM**

We claim the ornamental design for side hand rails of a treadmill, as shown and described.

DESCRIPTION

FIG. 1 is a side, front perspective view of side hand rails of a treadmill;

FIG. 2 is a first side view of the side hand rails of a treadmill of FIG. 1;

FIG. 3 is a second side view of the side hand rails of a treadmill of FIG. 1;

FIG. 4 is a front view of the side hand rails of a treadmill of FIG. 1;

FIG. 5 is a rear view of the side hand rails of a treadmill of FIG. 1; and,

FIG. 6 is a top view of the side hand rails of a treadmill of FIG. 1.

The broken lines immediately adjacent to the solid lines in the drawings represent the boundaries of the claim and form no part of the claimed design.

1 Claim, 5 Drawing Sheets
